UNITED STATES PATENT OFFICE.

ORVILLE S. HERSHY, OF CHICAGO, ILLINOIS, ASSIGNOR TO HERSHY MANUFACTURING COMPANY, OF CHICAGO, ILLINOIS, A CORPORATION OF COLORADO.

AUTOMOBILE LOCK.

Application filed April 12, 1926. Serial No. 101,300.

This invention relates to a lock adapted especially for automobiles, and is designed particularly for association with one of the operating units thereof. It may be connected with a steering mechanism, a change speed mechanism, a motor ignition circuit, or any other unit or system whose operation is required in the use of the vehicle.

The embodiment of my invention herein shown and described includes a switch which may be interposed in the motor ignition circuit. Such a switch is designed to be opened, thereby rendering the motor inoperative, whenever the lock is operated to interfere with use of an associated mechanism.

The present invention embodies certain improved features in the connection between the lock and switch by which a two-stage operation is effected, i. e., the switch may be opened in advance of actuation of the lock, whereby the motor only is disabled, or, by continuing further the movement of the parts, the lock is actuated, the ignition circuit remaining open throughout this last movement stage. In this manner I provide for a selective operation such that either the motor alone, or the motor and steering together, may be rendered inoperative. My invention is accordingly concerned with a combined lock and switch having the characteristics noted, and also with various other objects and purposes which will hereinafter appear.

In the drawings:

Figure 1 is a view in elevation of the front side of the lock housing, showing in section the steering post and column which passes therethrough;

Fig. 2 is a longitudinal section through the lock taken on line 2—2 of Fig. 3;

Fig. 3 is a similar view taken on line 3—3 of Fig. 2;

Fig. 4 which is a fragmentary view in elevation of the rear or under side of the lock housing, shows the ignition switch movement thereon;

Fig. 5 is a similar view showing the switch moved to an off position;

Fig. 6 which is a sectional detail similar to Fig. 2, shows the locking bolt as advanced to effective position;

Fig. 7 is a fragmentary view similar to Fig. 6, showing the control for the locking bolt as moved through the first stage of its cycle; and

Fig. 8 is a sectional detail taken on line 55 8—8 of Fig. 6.

The present lock may be contained within a housing A through which is an opening for accommodating a column B within which is extended a post C connecting a steering wheel 60 with the swiveled running wheels, usually at the front of an automobile. Secured fast to the post is a collar D having therein a groove or socket 9 which may be brought into register with an opening formed in the column. 65 An attaching plate E having one edge receivable within a slot in the housing may be connected thereto with the aid of screws 10, and serves as a medium for securing the lock housing to a fixed part of an automobile—70 its instrument board for example.

The locking mechanism herein shown includes a bolt 11 adapted to be projected through the column into the socket 9 so as to lock the steering post against rotation. 75 This bolt is yieldingly associated with a hollow plunger 12 wherein is accommodated a coiled spring 13 which bears with pressure against one end of the bolt. The outward movement of this bolt, relative to the plunger, 80 may be arrested by any suitable means. A second spring 14 exerts an opposite force on the plunger such as to retract the same whenever conditions will permit.

Associated with the plunger is a control means for the locking bolt. As shown, this comprises a lever or handle 15 which is extended from a hub 16 secured fast to one end of a rock shaft 17 which is disposed transversely of the plunger adjacent its outer end. 90 The shaft is cut away in the region of the plunger to provide a pair of obtusely related surfaces 18 and 19 with either of which the plunger end may engage. As shown, the plunger end so engaged is offset to provide at 95 20 a shoulder which acts as a stop to prevent movement of the rock shaft past the point which is indicated in Fig. 6. The retention of the rock shaft in the normal position of the parts is assured by a spring detent 21 100 100 which is pressed into a hole or socket 22 (see Fig. 3).

An annular groove 23 may be provided around the plunger as shown. Intersecting this groove is a longitudinally movable safety pin 24 having an operating head 25 exteriorly of the housing. As by means of a spring 26, the pin is normally projected outwardly,

as indicated in Fig. 3. One side of the pin which lies adjacent the plunger is provided with an arc-shaped cut 27 conforming generally to the curvature of the plunger. With the parts related as in Fig. 2, the pin stands in its normal outer position where it acts to interfere with the longitudinal movement of the plunger. If the pin be pressed inwardly, however, its arc-shaped cut will be so related to the surface of the plunger as to permit the latter to advance. It may be desired additionally to positively prevent movement of the locking bolt until after the rock shaft has been turned a definite distance, in which case a plate 28 is extended laterally from the shaft 17 in such manner as to lie in the movement path of the locking pin when the parts are in the normal position of Figs. 3 and 4. With the rock shaft moved to a second position, as in Fig. 5, this plate is moved out of the way of the locking pin, permitting its operation in the manner just described.

The operation of the lock may be controlled by any suitable key mechanism. For this purpose I prefer the use of a cylinder lock 30 operable with the aid of a removable key 31. At the rear end of the lock cylinder, I have shown a wire spring 32 coiled one or more times about a fixed pin 33 so as to present one of its arms 34 adjacent a lug 35 which is carried by the cylinder. A pin 36 which is disposed transversely of the plunger is engaged by the wire 34 in such manner as to be normally projected into the annular groove 23 of the plunger. It is only when the plunger has advanced to locking position that this pin may enter the annulus to hold the bolt against retraction. At all other times the pin bears against the periphery of the plunger in such manner as to permit a forward movement thereof in response to actuation of the handle 15.

Associated with a lock of the general character described, is a switch which may be interposed in an electrical circuit—the motor ignition circuit, for example. Such a switch is preferably carried on the under side of the lock housing. As shown, it comprises an insulated block 37 on which are mounted a pair of spaced conductor plates 38 each of which terminates in a spring brush 39 bearing against the periphery of a disk 40 of insulating material. Extended diametrically across the face of the disk is a bar 41 having its ends 42 downturned over the disk edges, and preferably inset in flush relation therewith. Bearing upon the center of the bar is a spring tongue 43 which extends from a plate 44 also mounted on the block 37. Associated with the two plates 38 are terminals 45, a terminal 46 is also connected with the plate 44, and to each of these three plates may be connected electrical conductors (not shown) forming part of a three-wire circuit. In the disk edges may be

formed oppositely disposed notches 47 where-in the brushes 39 are receivable to serve as spring detents for holding the switch in an off position (see Fig. 5).

The disk 40 is mounted to rotate co-axially with the rock shaft 17, and may be drivingly connected thereto by a pin 48 (see Fig. 3). In the normal position of the lock parts shown in Fig. 2, the disk is rotatably disposed as shown in Fig. 4 whereby the circuit is closed between all the terminals, thus ensuring operation of the electrical apparatus connected therewith. If the rock shaft be rotated to the position of Fig. 7, there will be no advance of the locking bolt or its associated plunger, but the switch will have been turned to the off position of Fig. 5. The circuit is now open in this first stage of the lock operation whereby the motor or other associated apparatus is disabled. If the rock shaft be further moved to the position shown in Fig. 6, the locking bolt will be projected to the point where it may interfere with steering movements, and in this second stage of the lock movements the disk acts to hold open the circuit whereby the motor or other associated apparatus remains disabled.

The first stage of the lock operation, as just described, is reached without any interference on the part of the safety pin, since the plunger is not required to advance in any degree. At no time, while the switch remains closed, is it possible to advance the locking bolt whereby to disable the steering mechanism. This is due to the provision of the plate 28 which normally underlies the safety pin, its withdrawal from effective position taking place only when the rock shaft is first turned to break the electrical circuit. Before entering upon the second stage of the locking operation, however, the safety pin must be pushed in to release the plunger for movement. The advance of the locking bolt then results from further turning of the rock shaft whose final position is determined by engagement of its surface 18 with the stop shoulder 20, as indicated in Fig. 6.

In the use herein of the terms "open" and "closed" with reference to a motor ignition circuit, I have in mind the system of ignition motor generally employed, but knowing that magneto-equipped motors may be operated on an open circuit, which is the reverse of the prevailing kind, I would have these terms properly interpreted to describe the true situation. The various details of construction hereinbefore set forth are manifestly susceptible of embodiment in forms other than the precise one shown, and any such modifications, in so far as they fall within the purview of the claims below, are to be considered as within the limits of my invention.

I claim:

1. In a lock, the combination with an operating member, of a bolt movable into engage-

- ment with said member to oppose operation thereof, a control means for the bolt movable through a first portion of its cycle before actuating the bolt, and a releasable stop for normally preventing movement of the bolt, said stop being releasable only when the control means has advanced through the first portion of its movement cycle, substantially as described.
10. 2. In a lock, the combination with an operating member, of a bolt movable into engagement with said member to oppose operation thereof, a rock shaft having two obtusely related surfaces adjacent the outer bolt end whereon is provided a shoulder, and control means for turning the rock shaft whereby to advance the bolt, the rock shaft being movable through a portion of its cycle without advancing the bolt and then acting to project the bolt, one of said shaft surfaces being engageable with the shoulder to determine the final position of the shaft, substantially as described.
3. In a lock, the combination with an operating member, of a bolt movable into engagement with said member to oppose operation thereof, spring means tending to retract the locking bolt, and a control means having two movements stages adapted in the second stage to advance the bolt against the tension of said spring means, substantially as described.
4. In a lock, the combination with an operating member, of a bolt movable into engagement with said member to oppose operation thereof, a two-stage control means for the bolt freely movable through the first stage before advancing the bolt, a releasable stop for normally holding the bolt against movement, and means associated with the control means and co-operating with the stop to prevent actuation thereof until after the control means has moved into its first stage, substantially as described.
5. In a lock, the combination with an operating member of a bolt movable into engagement with said member to oppose operation thereof, a rotatable control means for the bolt, a switch associated with said rotatable means comprising a disk, a pair of connected segments oppositely disposed on the disk edges, and a pair of spring brushes bearing against the disk and completing an electrical circuit when in engagement with the connected segments, substantially as described.
55. 6. In a lock, the combination with an operating member of a bolt movable into engagement with said member to oppose operation thereof, a rotatable control means for the bolt, a switch associated with said rotatable means comprising a disk, a pair of connected segments oppositely disposed on the disk edges, a spring brush bearing on the segment connection adjacent the disk axis, and two other brushes bearing against the disk edges and adapted to close an electrical circuit when engaged by the connected segments, substantially as described.
7. In a lock, the combination with an operating member of a bolt movable into engagement with said member to oppose operation thereof, a control means movable through two stages in the latter of which it actuates the bolt, stop means preventing advance of the bolt until after the control means has been moved, and a switch associated with the control means adapted to open an electrical circuit with movement of said control means through its first stage, substantially as described.
8. In a lock, the combination with an operating member of a bolt movable into engagement with said member to oppose operation thereof, a rotatable control means for the bolt, a switch associated with said rotatable means comprising a disk, conductor means carried by the disk, and spaced brushes bearing against the disk and completing an electrical circuit when in engagement with said conductor means, substantially as described.
9. In a lock, the combination with an operating member of a bolt movable into engagement with said member to oppose rotation thereof, a rotatable control means for the bolt, a switch associated with said rotatable means comprising a disk, conductor means carried by the disk, and contacts with which said conductor means are engaged when the disk is in one rotative position whereby to complete an electrical circuit, substantially as described.
10. In combination, a steering column lock for a motor vehicle comprising a casing surrounding said column provided with an axially movable plunger, a lock controlled rotatable cam for causing axial movement of said plunger, a rotatable electric switch element mounted in said casing having simultaneous rotative movement with said cam, and a spring detent engageable with said switch element for resiliently retaining said switch element and said cam in a predetermined rotative position, substantially as described.
11. In a coincidental lock, a slidably movable locking member, an ignition circuit make and break mechanism, rotary means for slidably moving said locking member in a plane perpendicular to the axis of said means to locking position, said means being operable for moving said locking member to unlocked position without closing the ignition circuit, and for closing the ignition circuit upon further movement thereof, and automatically movable means for holding said means in the second-named position, substantially as described.
12. In a coincidental lock, a slidably movable locking member, an ignition circuit make and break mechanism, means for moving the

locking member from locking position prior to the closing of the ignition circuit, and automatically movable means for holding said locking member in "off" position and said make and break mechanism in "open" position, substantially as described.

13. In a coincidental lock, a slidably movable locking member, a rotatable ignition circuit make and break mechanism, means for 10 slidably moving said member to locked position and for rotating said make and break mechanism to "off" position, said means also moving said locking member from locking position without rotating said make and 15 break mechanism to "on" position, and automatically movable means for holding said locking member and make and break mechanism in said last-named position, substantially as described.
14. In a coincidental lock, a slidably movable steering post locking bolt, a make and break mechanism for the ignition circuit comprising stationary members and a rotatable contact member, means for slidably moving 25 said bolt to locking position and rotating said contact member to "off" position to open the ignition circuit, and for later moving said

bolt to unlocked position without closing the ignition circuit, substantially as described.

15. In a coincidental lock, a reciprocable 30 locking member, a rotatable ignition circuit make and break mechanism, means for sliding said locking member to locked position and for rotating the make and break mechanism to "off" position, said means being operable to slide said locking member from locking position without rotating the make and break mechanism to "on" position, means for preventing the return of said locking member to locked position, and further 35 means for holding said make and break mechanism in "off" position with said locking member in the last-named position, substantially as described.

16. In a coincidental lock, a reciprocable 40 locking bolt, a rotatable make and break mechanism for the ignition circuit, means for sliding said bolt to locking position and rotating said mechanism to "off" position to open the ignition circuit, and for later sliding 45 said bolt to unlocked position without closing the ignition circuit, substantially as described.

ORVILLE S. HERSHY.
